UNITED STATES PATENT OFFICE.

ARTHUR SCHOSHUSEN, OF PITTSBURG, KANSAS.

BOOT OR SHOE FORMER.

1,385,719.

Specification of Letters Patent. Patented July 26, 1921.

Application filed August 13, 1919. Serial No. 317,388.

To all whom it may concern:

Be it known that I, ARTHUR SCHOSHUSEN, a citizen of the United States, residing at Pittsburg, in the county of Crawford, State 5 of Kansas, have invented a certain new and useful Improvement in Boot or Shoe Formers, of which the following is a complete specification.

The present invention relates to boot and 10 shoe forms and aims to provide an improved and simplified form of light and adjustable construction, adapted to be readily and conveniently fitted inside the boot or shoe.

Accordingly one of the objects of the invention is to devise a novel shoe form structure comprising toe and heel portions, with the toe portion of the form composed of sections having provision for both lateral expanding movement as well as for adjustment 20 angularly for the purpose of fitting the toe portions of varying types of shoes.

A further object of the invention is to provide a form structure of this character in which provision is made for producing both a yielding separating movement of the toe and heel portions as well as a simultaneous spreading action of the sections of the toe portion of the form.

It is also sought to devise a shoe form 30 of this general type in which the heel portion of the form is combined with an instep portion, and the parts are so connected as to permit a maximum relative swinging movement or "break" of the parts of the form.

With these general objects in view, the invention will now be described with reference to the accompanying drawing illustrating one practical form of embodiment of the improvement, the particular features of 40 novelty of which will thereafter be pointed out and defined in the appended claims.

In the drawing—

Figure 1 is a sectional side view (partly broken away) showing a boot or shoe form 45 embodying the present features of improvement;

Fig. 2 is an inverted plan view of the same, with broken lines showing adjusted positions of the toe sections of the form;

Fig. 3 is a side view of a form showing a modified type of heel portion; and

Fig. 4 is an enlarged sectional detail view of the spring member for expanding the toe sections of the device.

Referring now to the said drawing in de-

tail, this illustrates the improved form as comprising a sectional toe portion, made in two sections 5, and a heel portion 6, which in the type shown in Figs. 1 and 2 is combined with an instep portion 7 which extends forward into overhanging relation to the rear ends and practically all of the ball portions of the toe sections 5. A pin 8 connects the forward portions of the toe sections 5, said pin being secured to one of 60 said sections and having its head loosely and slidingly received in a socket 9 of the other section 5 for permitting both lateral spreading movement as well as angular adjustment movement of said sections relatively to each other.

In opposite mating recesses 10 at the rear end portions of the toe sections 5 is mounted a pair of lever elements 11, each pivotally and loosely connected at its forward 75 end to a pin 12 secured to the corresponding toe section. Near their rear ends said lever elements 11 are fulcrumed on a pin 14, and said rear ends of the levers are embraced by an annular spring element 15 80 having its ends resting in notches 16 (see Fig. 4) near the ends of the levers in such a way as to tend to spread apart the front ends of the levers and thereby separate the toe sections 5. A link 17 engaging pins 18 85 carried by the levers 11 serves to limit the spreading movement of the latter in response to the spring's action. The spring 15 is swiveled upon the front end of a rod 20 which telescopes within a sleeve 22 having its rear end suitably fitted and retained within the heel portion 6 of the form. A spring 23 is coiled about the rod 20 and sleeve 22 within a recess 24 provided for said parts in the base of said heel portion 6, 90 and by abutment against the rear end of said recess and the spring element 15, respectively, exerts a yielding action tending to normally separate the toe and heel portions of the device. A plate 25 secured 95 transversely across the front end of the recess 24 by means of a pin 26 serves to slidably support the spring element 15 at the front end of the rod 20, thus holding all the connections between the parts of the 100 form in their proper relative positions.

The above described construction, including the instep portion 7, is that which is adapted for ordinary top or low top shoes, while for pumps the form illustrated in Fig. 110

3 is preferable, in which type of construction said instep portion is omitted and the small heel portion 6' is provided instead.

The invention thus provides a simple and practical self-adjusting form structure fulfilling the desired requirements. No parts of the device need be manually adjusted, as the form on being inserted into the shoe adjusts itself automatically to fill out all the parts of the toe and instep by expanding forwardly and laterally into engagement with the shoe upper on all sides, under the action of the springs 15 and 23. The provision of the laterally and angularly adjustable toe sections enables the form to adjust itself readily to various styles of toes, such as wide and narrow or pointed toes, as will be readily understood by reference to Fig. 2. Further, the cut of the instep and its overhanging relation to the toe sections, and the manner in which the same is arranged to swing with reference to the toe sections, provides a sectional form having an extreme break whereby the device is readily inserted into or removed from the shoe.

While I have illustrated and described what is now regarded as the preferred form of construction for embodying my improvement, I desire to reserve the right to make such formal changes or modifications as may fairly fall within the scope of the appended claims.

What I claim is:

1. A shoe form comprising a sectional toe portion and a heel portion, the sections of said toe portion being separately and independently movable and both laterally and angularly adjustable to fit the toe portion of the shoe, and means connecting said toe and heel portions of the form including means for automatically and yieldingly separating said toe and heel portions while simultaneously expanding said toe sections.

2. A shoe form comprising a sectional toe portion and a heel portion, and means connecting said toe and heel portions including a lever connected with each of the sections of said toe portion, and a spring associated with the rear ends of said levers and actuating the same to normally expand said toe sections.

3. A shoe form comprising a toe portion formed of separate and independently movable sections and a heel portion, and means connecting said toe and heel portions including a lever having a loose pivotal connection with each of the sections of said toe portion permitting independent angular adjusting movement of said sections to fit the toe of the shoe, and spring means acting to yieldingly separate said toe and heel portions of the form while simultaneously actuating said levers to normally expand said toe sections.

4. A shoe form comprising a sectional toe portion and a heel portion, a lever connected with each of the sections of said toe portion, and means connecting said levers with the heel portion including an annular spring element embracing the rear ends of said levers and actuating the same normally to expand said toe sections.

5. A shoe form comprising a sectional toe portion and a combined instep and heel portion, the sections of said toe portion being separately and independently movable and both laterally and angularly adjustable to fit the toe portion of the shoe, and means connecting said toe and said instep and heel portions of the form including means for automatically expanding said toe sections.

In witness whereof I hereunto affix my signature.

ARTHUR SCHOSHUSEN.
